Des. 221,849
Patented Sept. 14, 1971

221,849

FISHING FLOAT

Leo J. Spade, Nashville, Kans. 67112

Filed May 20, 1970, Ser. No. 23,068

Term of patent 14 years

Int. Cl. D22—05

U.S. Cl. D22—30

FIG. 1 is a perspective view of the fishing float incorporating my new design;

FIG. 2 is a front elevational view;

FIG. 3 is a rear elevational view; and

FIG. 4 is a bottom plan view.

I claim:

The ornamental design for a fishing float, as shown.
